UNITED STATES PATENT OFFICE.

SIDNEY M. BARNARD, OF FORESTVILLE, CONNECTICUT.

CATTLE-STANCHION.

SPECIFICATION forming part of Letters Patent No. 746,913, dated December 15, 1903.

Application filed January 10, 1903. Serial No. 138,525. (No model.)

To all whom it may concern:

Be it known that I, SIDNEY M. BARNARD, a citizen of the United States of America, residing at Forestville, in the county of Hartford and State of Connecticut, have invented 5 certain new and useful Improvements in Cattle-Stanchions, of which the following is a specification.

The object of the improvement is the production of a stanchion for four-footed beasts, having certain features of novelty and advantage.

In the accompanying drawings, Figure 1 is a general front view of the device. Fig. 2 is 15 a sectional view on the line $x-x$ of Fig. 1 looking in the direction of the arrows. Fig. 3 is a top view of the device.

In the drawings the letters a and b denote two uprights of the stanchion-frame, preferably of wood, because its non-conducting qualities as to heat makes it neither cold nor hot to the animal's neck and because it wears smoothly. One of these stanchions b is pivotally hung and supported at its foot in order 25 that it may be swung outwardly to admit the head of the creature, after which it is swung back to place and suitably fastened, as hereinafter described. These uprights are connected at each end, front and rear, by metallic strips adapted for the adjustment of the uprights toward and from each other. The letter c denotes two such strips bolted to the foot of the upright a . The letter d denotes two such strips connected to the foot of the 35 upright b by a bolt, which is also a pivot for the hereinbefore-described swing of the upright b . The strips c carry the mortise c' .

The letter e denotes a headed bolt properly equipped with a nut which traverses the mortises c' and also coöperating holes in the strips d , between which it carries the sleeve e' . Said bolt, sleeve, mortises, and bolt-holes constitute an arrangement whereby the lower ends of the two uprights may be adjusted 45 toward and from each other and properly fastened in such adjustment.

The letter f denotes metallic strips rigidly bolted to the upper ends of the upright a .

The letter g denotes metallic strips appurtenant to the upper end of the upright b .

The strips f carry the mortises f' .

The letter h denotes bolts equipped with

proper nuts and carrying the sleeves h' . There are holes for these bolts through the strips g . These last-mentioned bolts, mortises, sleeves, and bolt-holes constitute an arrangement whereby the upper ends of the two uprights may be adjusted toward or from each other and held in that adjustment.

The upper end of the upright b is inwardly beveled at b' to coöperate with a spring-retainer, which will now be described. This spring-retainer (denoted by the letter i) is coiled about one of the bolts h , has proper bearing at the rear end, and at the other end 60 takes over the upper end of the upright b . By raising the outer end of this retainer the upper end of the upright b is unlocked and may be swung outward for the purposes already stated, and when it is swung inward the outer 65 end of the spring-retainer rides up on the bevel b' and takes that upper end of the upright b into its hold.

The strips c are provided with inturned flange c^2 , which takes into corresponding cross-mortise in the upright b . The strips f are each provided with inturned flange f^2 , which takes into corresponding cross-mortise in the upper part of the upright a . Each of the strips g is provided with an inturned flange g' , which takes into a corresponding cross-mortise in the upper part of the upright b . These inturned flanges taking into co-operating mortises, as described, serve to help to retain the proper relation of the uprights 85 to the strips in a very marked and emphatic degree.

I claim as my improvement—

1. A stanchion-frame comprising two uprights, and metallic strips of adjustable length 90 uniting the ends of said uprights.

2. A stanchion-frame comprising an upright, and metallic strips of adjustable length secured front and rear to the ends thereof; and a second upright pivotally supported at 95 one end by one set of the above-mentioned strips, the other end of said upright being adapted for engagement with and disengagement from the other set of strips, substantially as described and for the purposes set forth.

3. The stanchion-frame composed of two uprights, a metallic strip uniting said uprights at the ends and having an inturned flange

projecting into a corresponding cross-mortise in the upright.

4. In combination, in a stanchion-frame; two uprights, one pivotally supported at its 5 foot and inwardly beveled at the top; metallic strips uniting the stanchions at each end front and rear; a bolt midway of the upper ends of the uprights supported by metallic strips; and a spring-retainer between said

strips last mentioned encircling said bolt and 10 coöperating with said beveled upper end of the pivotally-supported upright.

In testimony whereof I affix my signature in presence of two witnesses.

SIDNEY M. BARNARD.
